UNITED STATES PATENT OFFICE.

GEORGE HENRY BAUST, OF OMAHA, NEBRASKA.

SANITARY KIT FOR BUTCHERS' KNIVES.

Application filed October 2, 1922. Serial No. 591,976.

To all whom it may concern:

Be it known that I, GEORGE H. BAUST, a citizen of the United States, residing at Omaha, in the county of Douglas and State 5 of Nebraska, have invented new and useful Improvements in Sanitary Kits for Butchers' Knives, of which the following is a specification.

The object of this invention is to provide 10 a case for the knives used by butchers engaged in slaughtering, the receptacle being constructed of metal, and adapted to be sterilized in hot water, whereas the leather case commonly in use can not be kept in 15 sanitary condition.

A further object is to provide a case of 20 this type with suitable means for supporting the knives in vertical position without danger of dulling them, and to provide a hinged element formed with slots or the like, through which a supporting belt may be passed.

With the foregoing and other objects in view, the invention consists in the novel 25 construction and arrangement of elements described, illustrated, and claimed, it being understood that modifications may be made within the scope of the claims, without departing from the spirit of the invention.

30 In the drawing, Figure 1 is a perspective view of the device, the knives being shown in dotted lines.

The case is preferably formed of aluminum and includes a back 10 formed in two 35 sections, the upper portion being designated 10' and connected with the main portion by a hinge 11, formed by rolling the ap-

proaching edges and providing a pintle 12. The hinge permits the back 10, 10' to yield when the device is suspended from the waist 40 of the user and when assuming a bending position.

Portion 10' is slotted at 13 and 14 and accommodates the belt 15.

The front wall 16 is connected by side or 45 edge portions 17, 18 with the back, and the box-like receptacle thus formed may be wider at the top than at the bottom, permitting of the easy insertion of the knives 19, 20. In order to prevent damage to the 50 points of the knives, a strip of rubber 21 is placed on the bottom 22, and may readily be cleansed when the metallic case is sterilized.

What I claim is—

1. A device of the class described, comprising upper and lower sections, a hinge for connecting said sections along a transverse line, the upper section being provided with slots, a belt passing through the slots, an open-top receptacle carried by the lower section, and a strip of flexible material on the upper side of the bottom of the receptacle.

2. A device of the class described, comprising hingedly connected sections of sheet metal, an open-top metallic receptacle carried by one of the sections, the other section being slotted, and a supporting device constituting a waist belt, passing through the 70 slotted portion.

In testimony whereof I affix my signature.

GEORGE HENRY BAUST.
